GARMENT CLASP

Randall B. Young, Akron, Ohio

Application December 24, 1936, Serial No. 117,524

7 Claims. (Cl. 24—247)

This invention relates to garment clasps, and, while intended for use generally wherever it may be advantageously applied, it is particularly adapted for use as a garter clasp in which connection it is illustrated in the drawing and hereinafter specifically described.

Objects of the invention are to provide a clasp of simple, economical construction which may be conveniently used for securely attaching a supporting member to a stocking or other garment.

Other objects are to provide a garter clasp having a base member and a loop member with an elongated stud adapted when turned longitudinally of the loop to be received therein and arranged when turned transversely of the loop to engage the loop and hold the same in an operative position and to provide simple, efficient means for locking the clasp in a closed position.

The above and other objects and advantages are accomplished by the novel construction hereinafter described with reference to the accompanying drawing in which the invention has been illustrated as applied to a particular structure, it being understood that the structure illustrated may be changed or modified in various ways and adapted to other purposes which come within the spirit of the invention as hereinafter claimed.

In the drawing:—

Figure 1 is a front, elevational view of a clasp constructed in accordance with this invention, the same being shown with the stud in an operated position.

Figure 2 is a similar view showing the stud in a locked position.

Figure 3 is a similar view showing the base portion of the stud in cross section as the same is positioned when the head of the stud is in an inoperative position.

Figure 4 is a similar view showing the base portion of the stud in cross section, the same being taken with the stud in a locked position.

Figure 5 is a side elevational view of a clasp constructed in accordance with this invention.

Figure 6 is a central, vertical, sectional view taken as indicated by the lines 6—6 of Figure 1.

Figure 7 is a fragmentary, longitudinal view of the upper portion of a stocking showing the clasp in a partly closed position and showing by dotted lines the manner of initially positioning my improved garter clasp thereon.

Figure 8 is a similar view showing the clasp in an operated position.

Figure 9 is a front, elevational view of a modified form of the invention, the same being shown in an open position.

Figure 10 is a side elevational view of same, Figure 11 is a front, elevational view showing the same in a locked position.

In the particular form of the invention shown in the drawing, the numeral 15 denotes a flat back member which may be composed of any suitable material, but is preferably composed of relatively stiff, sheet material. The numeral 16 denotes a loop member which is hingedly secured to the back member 15 by means of the staples 10 or other suitable fastening means.

The numeral 18 denotes a stud which is secured to the back member 15 by means of a rivet 20. The rivet 20 is provided on the rearwardly presented end thereof with a flat head which has a diameter greater than the opening 19.

The upper portion of the opening 19 is circular and is provided with a relatively narrow, downwardly projecting extension 19a. The shank portion 20a of the rivet 20 is of elongated, rectangular shape and is adapted to fit in the lower portion 19a of the opening 19 when positioned with its longer sides disposed longitudinally of the extended portion 19a of the opening 19. A washer 18a of approximately the same diameter as the head of the rivet 20 is positioned on the rivet between the stud 18 and the elongated portion 20a. With the clasp in an open position, the elongated portion 20a is freely rotatable in the opening 19 as shown in Figure 3. With the clasp in a locked position, as shown in Figure 2, the elongated portion 20a of the rivet 20 is locked against rotation as shown in Figure 4. The head of the lug 18 is elongated with the end portions thereof overhanging so that when turned longitudinally of the loop 16, it will not engage the loop member 16, but when turned transversely of the loop as shown in Figure 1, will overlap the members of the loop 16 to hold the same in position against the back of the member 15.

The back member 15 is provided at the upper end thereof with a cord 21 or other means by which the clasp is secured to the main body of a garter or other device.

In use, the stud 18 is turned to a position where it is disposed longitudinally of the clasp 16. The loop member 16 is swung to an open position and the upper portion of a stocking is positioned over the stud 18. The members 15 and 16 are swung to a horizontal position and the stud is held in a horizontal position while the back member 15 is swung to a vertical position, thus positioning the stocking covered stud in the position shown in Figure 8. In this position the elongated portion 20a of the rivet 20 is positioned in the upper por-

tion of the opening 19. The stud is then held stationary and the back member 15 and loop 16 are moved upwardly to position the portion 20a in the lower portion 19a of the opening 19 as shown in Figure 4. In this position, the head of the stud 18 is positioned transversely of the loop 16 with the elongated portion 20a of the rivet 20 fitted in the rectangular lower portion of the opening 19 thus locking the stud 18 against turning movement on the back member 15.

In Figures 9, 10 and 11 there is shown a back member 22 which serves the same purpose as the back member 15 and a loop member 23 which serves the same purpose as the loop member 16.

15 The back member 22 and the loop member 23 are formed of one piece of relatively stiff sheet material bent at 24 to form a hinge. The back member 22 is provided with an elongated stud which is similar to the stud 18 and which is rotatably 20 mounted on the back member 22.

25 The front member 23 is provided with an elongated opening 26 which will permit a free opening and closing movement of the front member 23 when the stud 25 is positioned longitudinally thereof as shown in Figure 9 and which is positioned on a stocking or other garment as above described and turned to the position shown in Figure 11.

30 In the adaptation of the invention shown in Figures 9, 10 and 11, a supporting cord 27, similar to the supporting cord 21, is positioned through the opening 26 and secured to the back member 22 by the rivet 28 which secures the stud 25 thereon.

35 While I have illustrated a lug 18 secured to the back member 15 by a rivet 20, it is understood that any suitable means may be employed for rotatably mounting an elongated lug on said back member and that the term "stud" as used in the 40 claims may be considered as including the stud 20 and the means by which it is attached to the back member 15.

Having thus illustrated my invention and described the same in detail, what I claim as new 45 and desire to secure by Letters Patent is:—

1. In a stud-type clasp for holding flexible material at points not provided with openings sufficiently large to receive the stud, the combination with front and back members having interconnected means for guiding said members to and from each other, a stud rotatably mounted on one of said members and having an enlarged head thereon elongated in a plane substantially perpendicular to the axis of said stud, the other of 50 said members having an opening of a size and shape to permit said head to pass therethrough when said stud is rotated relative to said first member to a given position, and through which said head can not pass when in at least one other given position relative to the member on which it is mounted, said latter position being the operative position of said stud whereby the garment material to which said clasp is to be attached may be placed over said head with the members 55 separated, and, with the stud in said first position the members may be brought together to cause the stud and overlying material to pass through said opening, after which the said members may be rotated to said operative position relative to said stud to prevent withdrawal of said head and material from said opening.

2. In a stud-type clasp for holding flexible material at points not provided with openings sufficiently large to receive the stud, the combination with front and back members pivoted to

each other a stud rotatably mounted on one of said members and having an enlarged head thereon elongated in a plane substantially perpendicular to the axis of said stud, the other of said members having an opening of a size and shape 5 to permit said head to pass therethrough when said stud is rotated relative to said first member to a given position, and through which said head can not pass when in at least one other given position relative to the member on which it is 10 mounted, said latter position being the operative position of said stud whereby the garment material to which said clasp is to be attached may be placed over said head with the members separated, and, with the stud in said first position the 15 members may be brought together to cause the stud and overlying material to pass through said opening, after which the said members may be rotated to said operative position relative to said stud to prevent withdrawal of said head and 20 material from said opening.

3. In a stud-type clasp for holding flexible material at points not provided with openings sufficiently large to receive the stud, the combination with front and back members having interconnected means for guiding said members to and from each other, a stud rotatably mounted on one of said members and having an enlarged head thereon elongated in a plane substantially perpendicular to the axis of said stud, the other 30 of said members having an opening of a size and shape to permit said head to pass therethrough when said stud is rotated relative to said first member to a given position, and through which said head can not pass when in at least one other given position relative to the member on which it is mounted, said latter position being the operative position of said stud whereby the garment material to which said clasp is to be attached may be placed over said head with the members separated, and, with the stud in said first position the 35 members may be brought together to cause the stud and overlying material to pass through said opening, after which the said members may be so rotated to said operative position relative 40 to said stud to prevent withdrawal of said head and material from said opening, said stud additionally being mounted for limited sliding movement on said first member, after said stud is moved to said second position, and means thereon 45 cooperating with means on said second member for locking said stud against rotation.

4. In a stud-type clasp for holding flexible material at points not provided with openings sufficiently large to receive the stud, the combination with front and back members having interconnected means for guiding said members to and from each other, a stud rotatably mounted on one of said members and having an enlarged, elongated head thereon, the other of said members having an opening through which said head will pass when said stud is rotated relative to said first member to a given position, and through which said head can not pass when in at least one other given position relative to the member on which it is mounted, whereby the garment material to which said clasp is to be attached may be placed over said head with the members separated, and, with the stud in said first position the members may be brought together to cause the 60 stud to pass through said opening, after which the said members may be rotated to said other position relative to said stud to prevent withdrawal of said head from said opening, said stud additionally having means thereon 65 cooperating 70

with means on said second member for locking said stud against rotation when said stud is moved to said second position.

5. In a stud-type clasp for holding flexible material at points not provided with openings sufficiently large to receive the stud, a back member, a front member having an opening and being carried by said back member, said back member being provided with an aperture having a 10 downwardly directed narrower extension, the side walls of said extension being substantially parallel; a lug having a shank portion of elongated cross-section rotatably mounted in said aperture and receivable in said extension when positioned 15 edgewise thereof, said shank portion having flat portions when entered in said extension engageable with said walls to prevent turning movement of said stud.

6. In a stud-type clasp for holding flexible material at points not provided with openings sufficiently large to receive the stud, a back member, a front member having an opening and being carried by said back member, said back member being provided with an aperture, said aperture 25 having a downwardly projecting narrower extension, a lug having a shank portion of elongated cross section rotatably secured in said aperture and fitting in said extension when presented with its largest portion substantially parallel to said 30 extension; said lug having an elongated head re-

ceivable in said opening in said front member when disposed longitudinally thereof and engaging said front member when entered therein and turned transversely thereof to prevent withdrawal from said opening; the elongated portion 5 of said shank being movable into said extension to lock said lug against turning movement substantially as herein set forth.

7. In a stud-type clasp for holding flexible material at points not provided with openings 10 sufficiently large to receive the stud the combination with a back member of a front member, a stud with an elongated head, means for rotatably securing the back member to the stud for relative turning movement with respect thereto, 15 guiding means for relative turning movement with respect thereto, guiding means interconnecting said front and back members to guide said members to and from each other in proper cooperating relation, said front member having an 20 opening for receiving the stud and providing an edge adjacent said opening for engaging the said head of the stud when the front member, carried by the back member, is turned to a given angular position with respect to the head, said head being 25 free of the edge of said opening in another angular position thereof to permit movement of the front and back members away from each other.
